Dec. 11, 1928.

1,695,153

L. Z. NELSON

SANITARY NAPKIN HOLDER

Filed July 21, 1927

FIG - 1

FIG - 2

FIG - 3

FIG - 4

Witness

Seamus

Lettie Z. Nelson

H. B. Wilcox & Co.

Attorneys

UNITED STATES PATENT OFFICE.

LETTIE Z. NELSON, OF ST. JOSEPH, MISSOURI.

SANITARY-NAPKIN HOLDER.

Application filed July 21, 1927. Serial No. 207,418.

The invention aims to provide a new and improved sanitary napkin holder, constructed to not only hold a napkin or any other desired pad, in position for use, but to carry a 5 spare napkin or pad and protect the latter against fluid from the pad in use. Thus, whenever necessary or advisable, the pad which has been in use may be disposed of and the spare pad used.

10 The term "napkin" will be hereinafter used in a sense comprehending any absorbent pad regardless of the material or materials from which it may be formed.

Fig. 1 of the accompanying drawing is a 15 perspective view of the device, two napkins being held therein.

Fig. 2 is a longitudinal sectional view.

Fig. 3 is a vertical transverse section on line 3—3 of Fig. 2.

20 Fig. 4 is a plan view partly broken away, both napkins being removed.

The drawing above briefly described, illustrates the preferred form of construction, and while this construction will be hereinafter 25 specifically described, it is to be understood that within the scope of the invention as claimed, numerous variations may be made.

The numeral 5 denotes an elongated sling sheet preferably narrowed somewhat towards 30 its ends. Connected to and extending along the longitudinal edges of the sheet 5, are two side walls 6. Interposed between these side walls, is a second sling sheet 7, the ends of the two sheets 5—7 and the side walls 6, being all connected with each other and provided with appropriate means such as straps 8 and buckles 9, for attachment to a belt or the like 10 of any desired form.

Any appropriate materials may be used 40 but I prefer thin, freely flexible, sheet rubber for the sling sheets 5—7 and the side walls 6. Said side walls are preferably stitched at 11 to the sling sheet 5 and these connected edges are preferably bound by rubberized fabric 12. Similar bindings 13 are provided on the free edges of the walls 6, and the edges of the sling sheet 7 are preferably bound in the same manner as at 14. Other bindings 15 of rubbered fabric, are provided at the extreme ends of the sling and it will be understood 50 that these bindings not only provide for a very durable device, but as the rubber is stitched between the two side portions of each binding, there is no danger of the stitching tearing loose.

55 The sling sheet 5 and the side walls 6 contact in forming a pocket for a spare napkin 16, which napkin underlies the second sling sheet 7. This sling sheet 7 supports a napkin 17 for use, between the side walls 6, and it will be observed that said sling sheet 7 effectively protects the spare napkin 16 60 against fluid absorbed by said napkin 17. Whenever advisable, the napkin 17 may be disposed of, the spare napkin 16 removed 65 from its retaining pocket and positioned upon the sling sheet 7, and then held in place for use.

The invention is not only rather simple and inexpensive, but is durable and possesses numerous advantages which will be apparent 70 to users of such devices, without further elaboration.

I claim:

1. A sanitary napkin holder for holding a 75 napkin when in use and provided with a pocket for carrying a spare napkin for emergency use.

2. A sanitary napkin holder comprising a sling for carrying two napkins one above the 80 other, and a moisture-proof sheet connected to the sling to extend between the two napkins, protecting the lower from fluid absorbed by the upper.

3. A sanitary napkin holder comprising a 85 sling sheet to support a spare napkin, side walls connected to the longitudinal edges of said sling sheet, and a second sheet between said side walls and connected to said sling sheet, said second sheet being adapted to support a napkin in use and serving to protect the underlying spare napkin.

In testimony whereof I have hereunto affixed my signature.

LETTIE Z. NELSON.